Attorney.

UNITED STATES PATENT OFFICE.

ALFRED L. RUTHVEN, OF ROCHESTER, NEW YORK, ASSIGNOR TO SIMPLEX TRAIN CONTROL COMPANY, INC., OF ROCHESTER, NEW YORK, A CORPORATION OF NEW YORK.

ELECTROMAGNETIC TRAIN CONTROL.

Original application filed October 8, 1918, Serial No. 257,836. Divided and this application filed February 19, 1921. Serial No. 446,304.

To all whom it may concern:

Be it known that I, ALFRED L. RUTHVEN, a citizen of the United States, residing at Rochester, in the county of Monroe and

6 State of New York, have invented certain new and useful Improvements in Electromagnetic Train Controls, of which the following is a specification, reference being had

10 to the accompanying drawing.

14 The present invention relates to railroad block signalling and automatic train or vehicle control, and is particularly an improvement over the electrical track circuit control disclosed in the copending application 18 for patent, Serial No. 215,300, filed February 4, 1918; this application being a division of the application filed October 8, 1918, Serial No. 257,836.

19 It is the object of the invention to provide novel and improved means of cooperation between the vehicle and track equipments for controlling the movement of the vehicle under the various traffic conditions, such means eliminating the use of electrical, 23 mechanical or other contact or similar devices between the vehicle and track, thereby removing a serious objection to train controlling apparatus embodying such contact devices. Another object is the provision of 25 such means between the vehicle and track or road bed utilizing magnetomotive force in a novel manner as the medium of control, to dispense with contact and like devices and their objectionable characteristics.

26 Another object is the provision of an improved magnetically responsive vehicle equipment controlling the movement of the vehicle, and also bringing the vehicle to a stop or retarding its movement should the equipment not be in operative condition, thereby preventing the vehicle from proceeding when its controlling means is defective.

30 A still further object is to improve the vehicle equipment so as to effectively retard the vehicle when danger is presented, and to permit the vehicle to proceed under caution at a slow speed, stopping it if the speed allowed is exceeded. This permits the vehicle to move, under the direction of the authorized person, after danger is signaled and the power shut off and brakes applied

automatically through the magnetic appliances, so that the operator can proceed with the vehicle or back up, such as for the purpose of moving into a siding for clearing the main line, or the like.

35 The invention also includes novel means for clearing the vehicle when proceeding under caution conditions, so that the impediment as to retarded speed is removed, and the vehicle again allowed to proceed unrestricted, but only when normal danger conditions are positively changed to clear conditions to avoid accidental clear signals.

40 Furthermore, the invention has for an object the provision of novel means for giving danger and clear signals on the vehicle, and keeping a record of the operation of the controlling means for subsequent inspection.

45 Another object is to provide novel and improved means for operating the engineer's brake valve automatically, and allow him to apply the brakes at any time but not release them under danger conditions.

50 With the foregoing and other objects in view, which will appear as the invention is more fully understood, the invention resides in the construction and combination of parts as hereinafter described and claimed, it being understood that changes can be made within the scope of what is claimed without departing from the spirit of the invention.

55 The invention is illustrated in the accompanying drawings, wherein—

58 Figure 1 is a general view of the apparatus, mostly in diagram;

60 Fig. 2 is a longitudinal vertical section of the magnetically responsive mechanism of the vehicle, taken on about the line 2—2 of Fig. 1;

65 Fig. 3 is a perspective view of the track equipment, part of the casing being broken away to show the interior mechanism;

70 Fig. 4 is a transverse section of the track device, showing it more in detail and in normal danger position; and

75 Fig. 5 is a diagrammatical view of a block signal system of simple circuits, with the present apparatus linked or connected thereto to provide the connecting medium between the ordinary block signals and controlling means on the vehicle.

80 The apparatus is used on the locomotive

of a train or other vehicle and the track or road bed, and controls the usual air brake system, which includes the air reservoir 1 from which the air flows through the engineer's brake valve 2 when permitted, to the brake or train pipe 4^a so as to supply the auxiliary reservoirs as usual. When the brake valve is moved to another position by means of its handle 3, the air 19 escapes from the brake pipe 4^a to the atmosphere through the port 4 thereby applying the brakes. The apparatus forming the present invention includes means for automatically operating the brake valve 2, among 15 other controlling means, and the various devices will be described separately under their respective captions.

Vehicle stopping control.

20 The apparatus embodies a main control for bringing the vehicle stopping or retarding means into operation, and this control, designated generally at 5, is housed in a suitable casing 6, having the door 6^a for 25 gaining access to the parts for purpose of repair, inspection, or the like. The door 6^a is under lock and key and has a window to make the parts visible to the operator or engineer.

30 Within the casing 6 is a main air valve 7 of the control having the stem 8 disposed horizontally, and any suitable oscillatory valve can be used. A recording device 9 is connected to the valve 7 so as to record 35 the number of operations thereof for subsequent inspection, and to thus keep an automatic check on the operator.

The valve 7 has connected thereto a pipe 11' leading from a speed control device 10 40 hereinafter described, to receive air from a pipe 21 leading to the device 10 from the air reservoir 1 or other source of pressure fluid, and the valve 7 is normally closed to prevent the flow of air past it, but the air 45 is ready to flow through said valve the instant that it opens. Said valve is a three-way valve and has connected thereto another pipe 11 and also a pipe 12 which are in communication. The pipe 12 has branches leading to a whistle or audible signal 35, visual signal 34, power interrupting means 13, and the brake valve operating means 25, and the valve 7 when in normal position connects the pipe 12 through the pipe 11 and valve 50 with the atmosphere, thereby permitting the air to escape from said signals and means. The signal 34 therefore normally indicates "clear", being operated pneumatically, and the means 13 and 25 are released for ordinary operation, both being under pneumatic control through the pipe 12. When the valve 7 is turned, however, it closes the escape port through the pipe 11, and establishes communication between the pipes 11' 55 and 12, so that air flows at once to the signals

and indicates, audibly and visually, "danger", and the air also flows to the power interrupting means 13 to operate same for cutting off the steam or other motive power of the vehicle. At the same time the air 70 flows to the device 25 for turning the brake valve 2 forcibly, even against the resistance on the part of the operator if he tries to stop the action, so as to apply the brakes, 75 and bring the vehicle to a halt.

An arm 23 having a weight is carried by the valve stem or shaft 8 and is normally raised, so that said arm will swing downwardly by gravity and turn the valve 7 to stop the vehicle, when said valve is released, 80 the weighted arm 23 being always ready to operate said valve when needed. A second arm 24' is also attached to the stem 8 and is connected to the core of the solenoid or electro-magnet 24 that is normally energized to 85 raise the arms 23 and 24' and retain the valve 7 in normal position. Should the solenoid or magnet 24 become dead by the operation of the apparatus or by accident thereto, the arm 23 is heavy enough to operate the 90 valve 7 under any condition and therefore stop the vehicle as described above. When the arm 23 swings downwardly by gravity, the valve 7 is operated for connecting the pipes 11' and 12. The reenergization of the solenoid again raises the arms 23 and 24' to again restore the valve 7 to normal clear 95 position. The solenoid 24, arms 23 and 24', recorder 9, and signals are all located within the casing 6 so as not to be interfered with. When the arms 24' and 23 are in raised position, the pipe 11' is disconnected from the pipe 12, and the pipes 12 and 11 are connected to the atmosphere.

Speed control device.

The device 10 which is operated under caution conditions for controlling the speed at which the vehicle may proceed, includes a body 14 having an oscillatory valve 16 mounted therein and provided with a handle 16^a that can be swung by the authorized person after a danger signal has been given and the vehicle stopping means brought into play. A passage 15 in the body 14 connecting the pipes 21 and 11' is normally closed by the valve 16 but a second passage 22 also connecting said pipe is normally open through said valve, said passages being alternately opened for clear and caution conditions. A valve rod 17 slidable in the body 14 also normally closes the passage 15 and has a port 18 to register with said passage when said rod is moved under excess speed. A piston 19 on the rod 17 moves within a cylinder 20 in the body 14 and a spring 19^a normally retracts the rod 17 and closes the passage 15 and opens another passage 12' in the body connecting the pipe 12 with the atmosphere. Passages 31 and 32 in the body 125 130

14 communicate with the rear end of the cylinder 20 and are controlled by the valve 16, the passage 32 opening into the atmosphere and the passage 31 communicating with the air supply passage 22 at the reservoir side of the valve 16. Another pair of passages 33^a and 33 in the body 14 communicate with the other end of the cylinder 20 and are controlled by the valve 16, the passage 33 leading to the atmosphere and the passage 33^a communicating with the passages 15 and 22 at that side of the valve 16 opposite to the reservoir connections. In normal position the valve opens the passages 32 and 33^a and closes passages 31 and 33, thereby letting air into the forward end of the cylinder and out of the rear end thereof so that the air moves the piston backward and retracts the valve rod 17 assisted by the spring 19, but when the valve 16 is turned by the handle 16^a, passages 32 and 33^a are closed and passages 31 and 33 opened, so that the air can escape from the forward end of the cylinder and is admitted into the rear end thereof to exert continued pressure tending to push the piston 19 and valve rod 17 forward. The valve rod 17 is thus controlled and operated pneumatically according to the position of the valve 16.

30 A governor 37 of any suitable sort is used to control the speed under caution conditions, and is connected by means of a sprocket chain 37^a, gearing 37^b, or the like, with a wheel or other part of the vehicle which rotates when it is in motion. The parts 37^a or 37^b can be taken to represent means which rotate during the motion of the vehicle to rotate the governor according to the speed of the vehicle. The governor controls the valve rod 17 through medium of a rocking lever 38 having one arm operatively connected to the governor 37 and its other arm in the path of the forward end of the rod 17 to prevent its forward movement unless the vehicle exceeds a certain predetermined speed which will cause the lever 38 to be swung sufficiently to release the rod 17. The end of the rod 17 preferably has a roller 38^a to contact with the lever or latch 38 and reduce friction. As a result, when the lever or handle 16 is swung to proceed under caution, so that the flow of air through the passage 22 to the means 13 and 25 is stopped and the air allowed to escape therefrom through the passage 12', thereby permitting movement of the vehicle, the air now tends to advance the piston 19 and rod 17, but this is prevented by the lever or detent 38 unless the allotted speed is exceeded when the rod 17 can move. This will close the escape passage 12' from means 13 and 25 and will open the passage 15 so that air flows through this bypass to the means 13 and 25 to actuate them for again stopping the vehicle.

Thus, when proceeding under caution, the speed allowed must not be exceeded, or else the vehicle will be automatically stopped.

The speed control device therefore permits the vehicle to proceed slowly in the danger zone, so that it can proceed or back up at will below a given speed to avoid collision or accident, and at the same time, the operator cannot put the automatic means out of effective condition for stopping the vehicle again.

When the track is clear and the valve 7 again returned to normal position, the valve 16 is returned by hand, so that the vehicle can proceed as usual.

Brake valve operating device.

The device 25 has been designed to operate the engineer's brake valve 2 in an effective manner, and it includes a cylindrical casing 26 above the brake valve, as shown, and the stem 27 of the brake valve extends up through the lower end of said casing and is connected by a key 27^a within a rotary head 28 seated upon said lower end of the casing. The head 28^a is rotatable within a ring 30 surrounding it and having a lower outturned flange clamped between the parts of the casing at its lower end, said ring also having an upper flange turned to overlap the head 28^a and retain it in place. The head 28^a has a stud 28 concentrically within the casing provided with a helical groove 28^b forming a screw entering the central opening of a piston 29 which is slidable in the casing above the member or stud 28. The piston 29 has a pin 29^a entering the groove 28^b and the piston is kept from turning by means of feathers 26^a in the casing engaging grooves in the sides of said piston. An expansion spring 30^a between the ring 30 and piston 29 normally raises said piston and forces the air therefrom through the pipe 12 which is connected to the upper end of the casing 26 that provides a cylinder for the piston. The key 27^a is made fast to the stem 27 and works within a notch or groove in the member or head 28^a so that when the piston 29 is in normal raised position, the stem 27 and handle 3 can turn as usual for applying the brakes, without actuating the parts of the operating device 25, but when the piston is forced down by the flow of air into the upper end of the casing or cylinder from the pipe 12, the pin 29^a in traveling in the groove 28^b will turn the head 28^a and thus turn the key 27^a and stem 27 to apply the brakes automatically. In other words, the key 27^a can move forward in the head 28^a but when the head turns in the same direction, the key 27^a when in normal releasing position for the brakes, will be carried with the head as it would be by turning the handle 3 for applying the brakes. In this way, the operating device does not interfere

with ordinary operation of the brake valve under clear conditions, but automatically applies the brakes in the event of a danger signal and maintains them applied, until the apparatus is cleared.

Track device.

Reference is now had to the device (claimed in application Serial No. 257,336 hereinbefore referred to) used on the track at the controlling points, which may be at selected intervals, along the track of which the rails are shown at 36. Each of these devices includes a pair of danger armatures 40 at opposite sides of a clearing armature 39 located at the center of the track, all mounted for up and down movement toward and away from the vehicle, and said armatures are of suitable length. These armatures are mounted within a casing 41 that is of non-magnetic material so as not to interfere with the magnet attraction between the track and vehicle devices, and as shown in Fig. 1 the top of the casing has longitudinal corrugations or depressions between the armatures for stiffening and reinforcing the top of the casing which can therefore be as thin as possible above the armatures. The armatures are carried by transverse crank-shafts 42 journaled within suitable bearings within the casing 41 and said shafts in being rocked will alternately raise the armatures 39 and 40 to active position. The casing protects the armatures from damage and interference owing to weather conditions, and the track device is also foolproof. As shown, the track device is operated electrically but it may be controlled mechanically, pneumatically, or otherwise. A cup 45 secured to the bottom of the casing 41 holds a solenoid 44, the core of which is connected, as at 43, to one of the rock shafts 42, in order that when the solenoid is energized, the armatures 40 are moved downwardly to inactive position, and the armature 39 raised to active position, under clear conditions. The armature 39 is heavier than the two armatures 40, in order that when the solenoid 44 is de-energized under normal conditions or by failure of the controlling means, the armature 39 will gravitate to inactive position and raise armatures 40 to operative position for signaling danger. Thus, the track device is normally at danger and will go to this position if the controlling means fails, to assure the fact that the track device will not clear the vehicle passing it unless the actual clear signal is given.

Figures 3 and 4 illustrate the track device more in detail than shown in Fig. 1, and in these views, the inclined ends of the casing 41 are shown, but the corrugations or depressions in the top of the casing are left out, so that their use is made optional. The

casing 41 is seated on and supported by one or more transverse supporting bars 100 and each of these bars is attached at its ends to the rails 36 so as to be supported thereby and thereby support the casing 41 and armatures from the rails instead of from the cross ties. In this way, the casing and armatures are maintained in fixed relation to the rails and the responsive vehicle devices which pass over the track device, in order that the relation of the track and vehicle devices will not be varied or disturbed by the yielding movement of the rails and ties under the weight of the vehicle thereon. The ends of the bar 100 pass under the rails 36, and said bar is provided near its ends with lips 101 overlapping the base flanges of the rails at the inner sides of said rails, and clamping jaws 102 are bolted or otherwise fastened to the ends of the bar 100 and have lips overlapping the base flanges of the rails on the outside to clamp the bar 100 in place, and permit its removal for purpose of repair. It is preferable to place insulation 103 between the bar 100 and rails 36, and this is necessary when the rails 36 are used as conductors, to prevent short circuit.

Figures 3 and 4 illustrate the bearings 104 of the rock shafts 42 in the form of pedestals secured on the bottom of the casing 41 and bars 100, and said rock shafts embody journal sections 105 and 106 journaled through the bearings 104 and the armatures, respectively, with crank arms 107 secured to the journaled sections 105 and carrying the journaled sections 106 to form the cranks. The journals are preferably of anti-frictional design so that the armatures move freely, and such bearings for the journaled sections 106 are inset in the sides of the armatures, as at 108.

Figures 3 and 4 also illustrate the lamination of the armatures longitudinally thereof with the laminee in vertical planes, whereby to avoid stray eddies of the magnetic flux, and to greatly enhance the attraction of the vehicle magnets to said armatures as they pass longitudinally thereover.

The bars 100 not only support the casing 41 above the cross ties with a suitable clearance, to allow the casing to yield with the rails 36, but said bars also serve as stays to prevent the rails from spreading. Attention is also directed to the fact that the construction of the rock shafts 42 enables the cranks thereof to be adjusted angularly relatively to one another by loosening the arms 107 on the journal sections 105.

Responsive vehicle device.

The vehicle equipment has magnetic means responsive to the armatures of the track device, and for this purpose, three electro-magnets 46, 47 and 48 are carried by the vehicle for vertical movement, the first

one 46 at the center of the track to respond to the armature 39 when raised for clearing the vehicle, the second one 47 above one rail 36 or adjacent to some other magnetic object 5 to be attracted thereto for retaining clear conditions, and the other magnet 48 arranged to move over one or the other of the armatures 40, according to the direction of travel, to be attracted thereto for indicating danger 10 and stopping the vehicle. Said magnets are slideable vertically within depending pockets of a casing 49 carried by the vehicle, in any suitable manner, and said casing is of non-magnetic material so as not to interfere with 15 the magnetism.

The clearing magnet 46 and clear retaining magnet 47 are movable simultaneously, and to this end a transverse rock shaft 50 is journaled in suitable bearings in the casing 20 49 and has arms 51 and 53 secured thereto from which the respective magnets 46 and 47 are suspended, the arm 53 being longer than the arm 51, as seen in Figure 2, whereby the magnet 47 moves a greater distance 25 than the magnet 46. In this way, when said magnets are moved upwardly, the magnet 47 will be sufficiently removed from the rail 36 so as not to be attracted thereto unless the magnet 46 is first attracted to the armature 39 in raised position which will move the magnet 47 closer to the rail 36 into attractive relation thereto, so as to maintain such attraction and retain the magnets 46 and 47 in attracted or responsive position, as seen 35 in Fig. 1.

A second transverse rock shaft 57 is also journaled in the casing 49 and has an arm 59 secured thereto from which the magnet 48 is suspended, so that said magnet is movable 49 independently of the others. It will be noted that the magnets move bodily up and down, and that their coils or windings move longitudinally of their vertical axes, so as to cause a powerful attraction of the magnets to the armatures over which they pass, when said armatures are in raised position. The rock shafts 50 and 57 have arms 55 and 61, respectively, depending within switch casings 58 and 63, whereby said arms operate 55 electrical switches and also have springs 81 connected thereto, tending at all times to swing said arms and raise the magnets, which will result whenever the magnets are de-energized. Each of the electrical switches operated by the arms 55 and 61 includes, as shown in Fig. 2 in connection with the arm 55, a switch arm 83 pivoted at its lower end to a base 84 having a binding post 85, and the switch arm 83 is connected by an insulating link 88 with the arm 55 (or 61). Adjustable stop screws 82 are carried within the casings 58 and 63 for limiting the movement of the arms 55 and 61, in order that both the upward and downward movement 65 of the magnets can be limited as desired.

according to the clearance wanted with respect to the armatures. The switch arm 83 carries a spring contact 86 to engage a contact terminal 87, when the respective magnet is lowered, and said switch arm has a second 70 spring contact 91 to engage an adjustable contact 90 of another terminal member 89 when the responsive magnet is raised. Each switch is of this construction, to provide for either a normal open or a normal closed 75 circuit, whichever is used. This permits of either a closed or open circuit for either switch under normal conditions, and adjustments can be made to suit the circumstances. 80

The ends of the pockets of the casing 49 containing the magnets are provided with removable points 80 for deflecting stray objects out of the way, and for cutting snow and ice in the winter season. 85

The electrical circuits of the vehicle equipment are supplied with the electrical energy from a generator 64 or other suitable source. The circuit of the solenoid or magnet 24 of the controlling valve 7 includes generator 90 64, conductor 60, magnet 24, conductor 68, armature switch 52 of a safety magnet 52, conductor 69, clear magnet switch, and conductor 65. The conductors 65 and 69 are connected to the binding post 85 and contact terminal 87, respectively, of the clear magnet switch, whereby the switch arm 83 normally connects said conductors when the clear magnet 46 is down, and since the armature switch 52 is normally closed, the circuit of magnet 24 will be normally closed so as to energize said magnets and raise the weight arm 23 to retain the valve 7 in normal position. It is evident that if the current fails, by the opening of either or both 100 of the switches in the circuit for that purpose, or by the failure of the vehicle equipment to be in operative condition, the magnet 24 will become dead, thereby releasing the valve stem or shaft 8 and permitting the 105 weight arm 23 to open the valve 7 for the flow of air to the signal devices and train or vehicle retarding means. This assures of the vehicle being given a danger signal and being stopped whenever the circuit of 110 magnet 24 is opened by the apparatus in operation or whenever the apparatus is not in operative condition, because of the failure of current or the like. The clear magnet switch is normally held closed due to the 115 fact that the magnet 47 is attracted to the rail 36 or other magnetic object, thus maintaining clear conditions as long as current flows through said magnet, but if it fails, then the magnets 46 and 47 go up by force 120 of their lifting spring 81, and the clear magnet switch therefore opens between conductors 65 and 69 and thus opens the circuit 125 of magnet 24.

The magnets 46, 47, and 48 are all nor- 130

mally energized, with the magnets 46 and 47 down and the magnet 48 up, as seen in Fig. 1. One of the circuits includes generator 64, conductor 66, normally closed danger magnet switch conductor 67, safety magnet 52 to keep it energized, conductor 54, magnet 48 in series with magnet 52, and conductor 65. Magnets 48 and 52 are thus normally energized, and failure of current 10 in magnet 48 will also de-energize magnet 52 so that switch 52^a opens and magnet 24 becomes dead. The attraction of the danger magnet 48 to the respective armature 40 in raised position will swing the arm 61 so as 15 to open the danger magnet switch and the circuits thereof, so that all magnets become dead. Thus, the magnet 24 is de-energized either by the release of the normally attracted clear magnets 46 and 47, or by the 20 response of the danger magnet to the track device, providing a double acting arrangement. The conductor 67 has branches connected to the magnets 46 and 47 both in parallel with the magnet 48 and with one another, and the return conductor 65 is also branched and connected to the magnets 46 and 47 to complete the shunt circuits thereof. In the danger magnet switch, the conductor 67, like the conductor 65, is connected 25 to the binding post 85 and switch arm 83, but owing to the difference in the normal position of the magnets of the two sets, the conductor 66 is connected to the terminal member 89 instead of the contact terminal 30 member 87 as with the conductor 69. This is done to provide closed circuits for both switches with the magnets 46 and 47 normally down and the magnet 48 normally up. Should the 35 current fail in any of the several circuits, a danger signal will be given and the train retarding or stopping means brought into action.

Operation.

45 In Fig. 1, the apparatus is shown in clear condition, the armature 39 being raised to attract the magnet 46, which in being moved downwardly will carry the magnet 47 into attractive relation with the rail 36, so that 50 the magnets 46 and 47 are held down against the tension of their spring 81, as long as said magnets are energized. This maintains clear conditions by holding the clear magnet switch closed, and the magnet 48 although 55 normally energized is held in raised position by its spring 81, so that the danger magnet switch is also normally closed. The vehicle can therefore proceed unrestricted as usual, but should the current fail in any of the 60 circuits, the magnet 24 will naturally become de-energized and the valve 7 will be operated by the weighted arm 23, to give the danger signals and operate the power interrupting means 13 and brake valve operating device 25, thus preventing the vehicle from

proceeding with a defective controlling apparatus. This same result is obtained should the vehicle pass one of the track devices in normal danger position. Thus, assuming that the armatures 40 are in raised position, 70 as seen in Fig. 4, the magnet 48 in passing over one of said armatures will be attracted thereto and moved downwardly, thereby opening the danger magnet switch between the conductors 66 and 67, and this will open the circuits of all three magnets 46, 47 and 48, as well as the circuit of magnet 52. The circuit of the magnet 24 is therefore opened at two places, viz, at the switch 52^a and at the clear magnet switch between the conductors 65 and 69. The switch 52^a is opened by deenergization of the magnet 52, and the clear magnet switch is opened by the release of the magnets 46 and 47 when they are de-energized. This provides for a double action, in that, danger conditions are brought about by either the response of the danger magnet or by the return of normally energized and responding clear magnets 46 and 47. The slightest downward movement of the danger magnet 48 opens the danger magnet switch so that current will not flow through any of the magnets. The magnet 48 being deenergized after the danger signals are given, will be returned or raised by its spring 81, but the magnets 46 and 47 having also been raised by their spring 81 will retain the clear magnet switch open during danger conditions, it being noted that during these conditions, the clear magnets 39 are down so as not to attract the magnet 46, and the magnet 47 is far enough away from the rail 36 or other magnetic object not to be attracted thereto unless the magnet 46 is first attracted and moved downwardly. These conditions will prevail until the apparatus is again cleared.

When the valve 7 is operated by the fall of the arm 23 whenever the magnet 24 becomes dead, whether intentionally or accidentally, the air will flow at once to the signal devices 34 and 35 to operate them pneumatically for indicating danger visually and audibly, and the air will then flow to the device 13 for shutting off the steam or other motive power. The air also flows into the upper end of the casing or cylinder 26 so as to force the piston 29 down, and its pin 29^a in working in the groove 28^b will rotate the stud or member 28 and thus operate the brake valve 2 to vent the brake pipe 4^a and apply the brakes.

Should it be desired to proceed under caution conditions, the operator or authorized person can swing the handle 16^a of the speed control device 10, so as to reverse the valve 16. This will close the passage 22 through which the air normally passes from the supply pipe 21 to the pipe 11' leading to the valve 7, and the passage 12' is opened, so

that the air can pass from the signal device 34, and devices 13 and 25 to the atmosphere. This allows the power to be again applied, and the spring 30^a will raise the piston 29 and return the member 28 so that the operator can release the brakes. The reversal of valve 16, however, opens the passage 15, and the passage 31 so that the air enters the cylinder 20 and tends to move the piston 19 and valve rod 17 forward, which is prevented by the lever or detent 38, when the vehicle is traveling below a predetermined speed. Should this speed be exceeding the predetermined speed the governor 37 being operated by centrifugal force will remove the lever or detent 38 from the end of the rod 17, and the air pressure against the piston 19 will therefore operate at once to move the rod 17 forward and bring the port 18 into register with the passage 15, while the passage 12' is now closed. Air will therefore flow from the pipe 21 through the passage 15 to the pipe 11' and valve 7 which remains in danger position. The danger signals are therefore again given and the vehicle stopped. This prevents the vehicle from traveling above the allotted speed in the danger zone, but still permits it to move slowly to pass into a siding or the like. When the vehicle is stopped under caution conditions, the valve 16 can be returned so that the air will again enter the forward end of the cylinder 20 to return the piston 19 and rod 17, as seen in Fig. 1, without releasing the brakes or power interrupting means, and if the vehicle has been stopped or is moving slowly, so that the lever or detent 38 is again in active position, the valve 7 can be reversed again to caution position without stopping the vehicle again unless the speed allowed is exceeded.

The caution and danger positions will be maintained, until the apparatus is positively cleared, and until such is the case the vehicle must either remain at rest or proceed slowly under caution conditions, as above described. When the track is clear, and a track device which the vehicle passes is in clear position with the armature 39 raised, the magnet 46 in passing thereover will be attracted thereto, thereby closing the clear magnet switch which will then be held closed by the magnet 47 remaining attracted to the rail 36. The circuit of the magnet 24 is now closed, because the switch 52^a remains closed when the magnet 48 is raised and energized, and the clear magnet switch is closed by the response of the clear magnet. The valve 7 is therefore returned to the clear position as before, and the vehicle can proceed unrestricted as above described, before the danger signal was given.

Track signal system and track devices.

Fig. 5 illustrates the conjunction of a

series of the track devices at intervals along the track with a block signal system of simple normal danger arrangement. The rails 36 are divided into the sections A, B, C, D, and E insulated from one another, 70 and electrically-operated semaphores 37 are located between the blocks, each of which contains two or more sections. As many track devices can be used as desired, and as shown, they are placed at the junctures 75 of the track sections and between the ends thereof. The signal system illustrated is a well known simple form and includes an electromagnet 70 connected to each pair of rail sections at one end and a track battery 80 71 connected thereto at the other end to complete a normally closed circuit for each section and maintain the magnet 70 energized. Each magnet 70 attracts and normally closes an armature switch 73 disposed in 85 signal circuits 72 of the semaphores 37, and each of said circuits also includes an armature switch 74 attracted and normally opened by a magnet 70 in the rear. Thus, taking one circuit 72, it includes the semaphore 37 between sections B and C, armature switches 73 at the ends of section C, armature switch 74 between sections A and B, and the solenoids or magnets 44 of the track device at the centers and forward ends 90 of the sections B and C. The normally opened switch 74 opens said circuit 72, so that the respective semaphore and track devices or armatures thereof are in normal danger position. This condition will also exist if sections C or D are occupied, because this will short circuit one of the magnets 70 of said sections to let the respective switch 73 open and the opening of the semaphore circuit at any one of the several points 100 will produce danger conditions. However, should a train enter section B, moving toward the left in Fig. 5, the magnet 70 of said section will be short circuited and therefore de-energized, so that its switch 74 will 105 close the circuit and thus move the semaphore and track devices to clear position, whereby the train can advance past the semaphore into the next block. When the train enters section C, the magnet 70 thereof will 110 be deenergized by the short circuit established, and even though switch 74 is again opened as well as switch 73 between sections B and C, a second normally opened switch 75 of the magnet 70 under discussion will 115 be closed by the deenergization of the said magnet 70, and thus close the circuit of the two magnets 44 in advance, so that the train can pass the respective train devices. The switch 75 forms a short circuit between the 120 battery 76 of the circuit 72, and the semaphore 37 and magnets 44 in rear, so that a train following in section B will be stopped because the said semaphore and last mentioned magnets 44 will be in condition to 125 130

65 indicate danger, although the train already working in the cylinder longitudinally toward and away from said stem, pressure fluid supplying means for said cylinder controlled from the track, a rotary member in said cylinder connected with said stem to let it turn for applying the brakes and to turn the stem with said member for applying the brakes by the movement of said member in one direction, said member having a screw portion having a screw connection with the piston, and means for moving said piston to return the parts when the pressure is relieved.

70 5 This arrangement is just one of many in which the present track devices can be used for controlling traffic, and the illustration is to be taken as typical to make the invention better understood.

75 6 Having described the invention, what is claimed is:

10 1. Vehicle controlling apparatus embodying a source of pressure fluid, pressure fluid operated danger-indicating and vehicle retarding means, a valve operable for the flow of pressure fluid from said source to said

15 means and normally shutting off such flow, said valve having an oscillatory stem, a weight connected to said stem to gravitate and turn the stem for such flow of pressure fluid, electro-magnetic means for raising

20 weight and holding it raised with the valve shutting off such flow, and traffic controlled means for energizing said electro-magnetic means.

25 7. Vehicle controlling apparatus embodying a brake valve having a rotary operating member, and automatic means for controlling said valve including a reciprocating member having a screw connection with the aforesaid member.

80 8. In a vehicle controlling apparatus, vehicle controlling means including a rotary controlling member, and automatic means controlling said means and including a reciprocating member having a screw connection with the first named member.

85 9. A vehicle controlling apparatus including vehicle controlling means having a rotary controlling member, and automatic means including a cylinder, a piston working in the cylinder, means for controlling the flow of pressure fluid into the cylinder 95 to move the piston in one direction, and a screw connection between said member and piston for turning said member when the piston is moved by pressure fluid.

90 10. Vehicle controlling apparatus embodying clear maintaining magnetic means normally responded to a track device, danger magnetic means to respond to the track device, and means for retarding the vehicle should either the first named means move 105 from responded position or the second named means respond.

100 11. Vehicle controlling apparatus according to claim 10 wherein the retarding means includes a normally closed electrical circuit 110 having switches for both magnetic means to be opened by the movement of the first named means from responded position or the response of the second named means.

115 12. Vehicle controlling apparatus embodying a clear magnet movable in response to a track armature, electro-magnetic means for retaining said magnet in responded position, a danger magnet movable in response to a track armature and controlling means for the vehicle permitting it to proceed when the clear magnet is moved in response to the corresponding track armature and the danger magnet is in normal position, and retarding the vehicle when either the clear magnet returns or the danger magnet responds.

120 13. Vehicle controlling apparatus embodying a brake valve having a rotary stem, a cylinder in the axis of said stem, a piston working in the cylinder, and a rotary screw member connected to said stem and having a screw connection with said piston.

125 14. Vehicle controlling means embodying a brake valve having a rotary stem, an operating member therefor movable longitudinally thereof, operating means for said member controlled from the track, and a screw connection between said member and stem.

15. Vehicle controlling apparatus embodying a brake valve having a rotary stem, a cylinder attached to said valve, a piston

- bodying a clear electro-magnet movable in response to a track armature, an electro-magnet to be attracted with respect to a magnetic object for retaining said clear magnet in responded position and movable therewith to be brought into operation, a danger electro-magnet movable in response to a track armature, a switch normally closed by the clear magnet when in responded position, a switch normally closed when the danger magnet is in normal position, and vehicle retarding means including a normally closed circuit having said switches therein for retarding the vehicle whenever said circuit is opened or current fails, a source of electrical energy for said magnets and circuit, and means for interrupting the flow of electrical energy to said magnets when the danger magnet is moved.
14. Vehicle controlling apparatus embodying a danger electro-magnet movable in response to a track armature, vehicle retarding means brought into operation by the movement of said magnet, and source of electrical energy for said magnet to maintain it energized, and a safety electro-magnet connected to the danger magnet and controlling the retarding means to retard the vehicle should the safety magnet detect a failure of current in the danger magnet.
15. Vehicle controlling apparatus embodying the combination with armatures along the vehicle track alternately movable to danger and clear positions, of a vehicle equipment having danger and clear electro-magnets responsive to said armatures, to place the vehicle in danger and clear it, respectively, and means operable manually when the vehicle is in danger for allowing it to proceed slowly until cleared.
16. Vehicle controlling apparatus embodying the combination with armatures along the vehicle track to alternately move to clearing and danger positions, of a vehicle equipment having clear and danger magnets to respond to the armatures, vehicle retarding means controlled by said magnets operable to stop the vehicle when the danger magnet responds to an armature and to permit the vehicle to proceed unrestricted when the clear magnet responds to an armature, and speed control means adapted to be brought into operation manually when the vehicle retarding means has been operated to stop the vehicle and operable to remove such restriction only when the vehicle proceeds below a given speed under danger or caution conditions.
17. Vehicle controlling apparatus embodying the combination with armatures along the vehicle track to alternately move to clearing and danger positions, and controlling means for moving said armatures according to traffic conditions, of a vehicle equipment including a danger magnet responsive to an armature, vehicle retarding means brought into operation when said magnet responds, speed control means governed by the speed of the vehicle operable to let the vehicle proceed below a given speed when the retarding means has been operated and again bringing said retarding means into operation if the said speed is exceeded, and a clear magnet responsive to a track armature for clearing the retarding means so that the vehicle can proceed unrestricted.
18. Vehicle controlling apparatus embodying a source of pressure fluid on the vehicle, vehicle retarding means operated by pressure fluid, means for establishing the flow of fluid from said source to said means and normally shutting off such flow, a danger magnet responsive to a track armature, means for bringing said flow establishing means into operation when the danger magnet responds, means operable to shut off the flow for caution conditions, means to re-establish the flow and be brought into operation when the last named means is operated, speed controlled means for preventing the re-establishing means from operating unless the vehicle exceeds a given speed, and means for restoring the normal position of the flow establishing means first mentioned including a clear magnet responsive to a track armature.
19. Vehicle controlling apparatus embodying movable magnetic means installed on the road bed of a vehicle track, traffic controlled means for moving said magnetic means from danger position, said magnetic means including a magnetic member and being operable for setting itself to danger position with said member in raised position, movable magnetic means on the vehicle responsive to the aforesaid magnetic member when it is in raised position, and vehicle controlling means controlled by the last named magnetic means, the last named magnetic means being arranged to move, when released, to danger position for controlling the last named means to retard the vehicle.
20. Vehicle controlling apparatus embodying a brake valve having a rotary stem, an operating member therefor movable longitudinally thereof, operating means for said member controlled from the track, and a screw connected between said member and stem substantially as and for the purpose described.
21. Vehicle controlling apparatus embodying a brake valve having a rotary stem, a cylinder attached to said valve, a piston working in the cylinder longitudinally toward and away from said stem, pressure fluid supplying means for said cylinder con-

trolled from the track, a rotary member in said cylinder connected with said stem to let it turn for applying the brakes and to turn the stem with said member for applying the brakes by the movement of said member in one direction, said member having a screw portion having a screw connected with the

piston, and means for moving said piston to return the parts when the pressure is relieved substantially as and for the purpose 10 described.

In testimony whereof I hereunto affix my signature.

ALFRED L. RUTHVEN.
